This invention relates to an attachment for clothes hangers. In particular it relates to an attachment for wire clothes hangers which is adapted to grip a clothesline so as to support and hold the hanger against sliding or turning movement thereon.

It is very common for a housewife to wish to hang a garment on a clothesline by means of a clothes hanger to either air or dry the garment. A clothes hanger will, of course, stay on a clothesline provided that there is no wind. However, any breeze will cause a clothes hanger to slide on the clothesline and a strong wind will cause the hanger to turn to such an extent that the hanger hook will come off the line. Attempts have been made in the past to overcome this difficulty by providing some type of auxiliary hook on a regular clothes hanger which is especially adapted to engage a clothesline. One type of such hook is that to be found in United States Patent No. 2,494,973 issued January 17, 1950, in which a hook has been provided which is integral with the hanger itself. This has the disadvantage of making the hanger more expensive than a regular hanger.

Various types of detachable devices have also been developed, such as those described in United States Patent No. 2,692,575 issued February 24, 1953 and United States Patent No. 2,915,274 issued December 1, 1959. However, the device of Patent No. 2,915,274 is very complex, while the device of Patent No. 2,629,575 has the requirements of simplicity but is difficult to attach to or detach from a clothes hanger.

I have now developed a simple attachment for attaching to clothes hangers which is extremely easy to attach to and detach from clothes hangers while also being able to rigidly hold the hanger on the clothesline. My attachment is intended primarily for use with a wire clothes hanger of the type which has a pair of oppositely-extending arms supported at the centre of the hanger by upwardly-extending portions which converge so as to form a notch, and which are connected by a twisted joint or other means above said notch.

The attachment of my invention comprises a substantially N-shaped strip of flat material formed such that a straight centre portion is joined at each end to an end of an outer straight portion so as to form small open angles between the centre portion and each outer portion. A protrusion is provided between one outer portion and the centre portion which is adapted to engage the notch in the hanger. The angles and distances between the centre portion and the outer portions are arranged such that the side containing the protrusion will securely hold a common wire hanger while the side which does not contain the protrusion will securely hold a clothesline. The protrusion can be joined to either the centre portion or the outer portion or to both and can be rectangular in configuration or it can be in the form of a pin. Particularly when a pin is used as the protrusion, two projections are provided which extend out from the face of the centre portion adjacent the protrusion and engage the upwardly-extending portion of the hanger. The projections prevent the hanger from pivoting about the pin.

The attachment can be formed from sheet metal or can be moulded from a plastic. When it is moulded from

2

plastic the protrusion and projections are generally formed integrally with the main part of the attachment.

My invention will now be described by reference to the accompanying drawings in which:

5 FIGURE 1 is a perspective view showing one embodiment of my invention for supporting a hanger upon a clothesline;

FIGURE 2 is a section of the device as shown in FIGURE 1;

FIGURE 3 is a perspective view showing a second embodiment of my invention for supporting a hanger upon a clothesline; and

FIGURE 4 is a section of the device as shown in FIGURE 3.

Referring now to the drawings, in which like reference numerals denote corresponding parts throughout the several views, FIGURES 1 and 3 show a wire clothes hanger W positioned in my attachment 10 with my attachment also gripping the clothesline L.

20 The wire clothes hanger W is of the type which has a pair of oppositely-extending arms 11 and 12 supported at the centre of the hanger by upwardly-extending portions 13 and 14 which converge so as to form a notch 15 and which are connected by a twisted joint 16 above said notch. The upwardly-extending portion 13 is continued above the twisted joint 16 and curved laterally and downwardly to provide a large clothes hanger 17, while the upwardly-extending portion 13 terminates slightly above the twisted joint 16.

30 The attachment 10 as shown in FIGURES 1 and 2 comprises a strip of flat material arranged such that a straight centre portion 18 is joined at each end to an end of two outer portions 19 and 20 so as to form small angles 21 and 22 between the outer portions 19 and 20 and the centre portion 18. A rectangular protrusion 23 is provided between the outer portion 19 and the centre portion 18 and is adapted to engage the notch 15 of the hanger W. When the hanger W is in position in the attachment 10, the protrusion 23 engages the upwardly-extending portions 13 and 14 thus preventing the hanger from pivoting in the attachment and the angle 21 as well as the distance between centre portion 18 and outer portion 19 are arranged so as to resiliently engage the oppositely-extending arms 11 and 12. The angle 22 as well as the distance between centre portion 18 and outer portion 20 are arranged so as to resiliently engage the clothesline L.

35 As shown in FIGURES 3 and 4, the attachment 10 has a pin 24 fastened between the outer portion 19 and the centre portion 18 which engages the notch 15 of the hanger W. This embodiment also shows two projections 25 and 26 which extend out from the face of the centre portion 18. The projections 25 and 26 are positioned to engage the twisted joint 16 of the hanger W in order to prevent the hanger W from pivoting about the pin 24.

40 It will also be understood that the projections 25 and 26 can also be used with the rectangular protrusion 23 in order to more rigidly hold the hanger W in the attachment 10.

45 What I claim as my invention is:

1. An attachment for a wire clothes hanger of the type which has a pair of oppositely-extending arms supported at the centre of the hanger by upwardly-extending portions which converge so as to form a notch, and which are connected by a twisted joint above said notch, comprising a substantially N-shaped strip of flat material formed such that a straight centre portion is joined at each end to an end of an outer straight portion so as to form small open angles between the centre portion and each outer portion, and a protrusion between one outer

portion and the centre portion which is adapted to engage the notch in the hanger, said protrusion completely bridging the space between said outer portion and said centre portion at a point intermediate the said ends of the centre portion.

2. An attachment as claimed in claim 1, wherein additional projections extend from the face of the centre portion adjacent the protrusion which engages the notch, said additional projections being adapted to engage the upwardly-extending portion of the hanger.

3. An attachment as claimed in claim 2, wherein the protrusion for engaging the notch is integrally formed with the centre portion and outer portion.

4. An attachment as claimed in claim 2, wherein the protrusion for engaging the notch is integrally formed with both the centre portion and the outer portion.

5. An attachment as claimed in claim 2, wherein the protrusion for engaging the notch is in the form of a pin between the centre portion and the outer portion.
